UNITED STATES PATENT OFFICE.

HARVEY L. PRESTON, OF HUDSON, WISCONSIN.

BRAKE-BEAM.

SPECIFICATION forming part of Letters Patent No. 396,383, dated January 15, 1889.

Application filed March 26, 1888. Serial No. 268,483. (No model.)

To all whom it may concern:

Be it known that I, HARVEY L. PRESTON, a citizen of the United States, residing at Hudson, in the county of St. Croix and State of Wisconsin, have invented certain new and useful Improvements in Brake-Beams; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to brake-beams for use upon railway-ears of every description, the constructive material of which is entirely metal, as iron, steel, or both.

The beam consists, mainly, of two rods of any suitable or desired form in cross-section, supported at their middle point in bearings branching from the fulcrum-bar upon which the brake-lever is mounted and spread sufficiently at the bearing-point to secure the requisite vertical stiffness for the brake-beam. Mounted in a suitable bearing at the opposite extremity of the fulcrum-bar, which thus becomes a strut for supporting and retaining the several rods, is a truss-rod the length of the strut, and consequently the distance between the bearing-points of the two rods and the truss-rod, being sufficient to give the beam thus formed the requisite strength in the direction of the greatest strain. The truss-rod is brought down to the two main rods near their extremities, and the three rods are there brought together and retained by means of a triple sleeve formed, preferably, of malleable iron, which sleeve also forms a seat for the brake-head. The truss-rod passes wholly through the sleeve, and upon its outer projecting end is formed a screw-thread fitted with a nut, by means of which the sleeve is brought into proper position and retained, while the two main rods terminate within the sleeve, abutting against a shoulder formed therein by the termination of the portion of the triple socket in which they are held, whereby the tightening of the nut on the end of the truss-rod cambers the main rods sufficiently to accommodate the face of the brake-shoe to the coning of the tread of the wheel.

The points of invention consist, generally, in the construction and arrangement of the parts as above described, and in the several features of detail as hereinafter more fully set forth.

The invention is illustrated in the accompanying drawings, in which—

Figure 1 is a rear view of the improved brake-beam and connections, showing the general form and arrangement of the several parts. Fig. 2 is an upper side view of the same. Fig. 3 is an enlarged cross-sectional view showing an inner end view of the sleeve and the manner in which the brake beam and head are held in place by the hanger. Fig. 4 is a detail view of the triple sleeve in position upon the rods; Fig. 5, a longitudinal section of the sleeve in planes indicated by the line 5 5 in Fig. 3; Fig. 6, an outer end view of the sleeve and the flange cap or washer for retaining the brake-head in place; Fig. 7, a detail view of the bearings branching from the end of the strut in which the two main rods are mounted; and Fig. 8, a cross-section of the beam, showing the form and position of the clamps for attaching the safety-hanger.

Like letters designate corresponding parts in all of the figures.

In the drawings, A A represent the main rods, and B the truss-rod, mounted in bearings a a and b, respectively, formed on the opposite extremities of the strut C. The brake-lever D is mounted in a slot, c, formed longitudinally in the strut C, and is fulcrumed therein by means of a bolt or pin, d, as shown in dotted lines in Fig. 7, passing through it and the sides of the strut. The bearings a a branch outwardly in each direction from the end of the strut to any desired extent, in order that the rods A A may be sufficiently separated to act each as a truss for the other to maintain the requisite vertical stiffness of the beam in a vertical direction, while the length of the strut may be as great as required in order that the rod B on each side of its bearing at the end of the strut may have a sufficiently bracing position to withstand any ordinary strain that may be applied in the direction of the length of the strut by means of the brake-lever D.

The rods A A are straight except as they are sprung together at each end for attach-

ing the sleeve E. The truss-rod B is bent in each direction from its bearing-point b toward the ends of the rods A A, and at a point near the ends of the same is bent slightly in 5 the opposite direction, so that its extremities assume a position substantially parallel to the direction of the rods A A. The ends of the three rods are bunched together and retained by means of a sleeve, E, which is formed 10 with a triple socket, e, in its interior, of a form to fit the combined bulk of the three rods when brought closely together. The portion of the triple socket which is intended to receive the extremity of the rod B extends 15 entirely through the sleeve, the rod B extending a sufficient distance beyond the outer end of the sleeve to receive the flange cap or washer F and the nut G, attached to the rod by means of a screw-thread formed thereon 20 at its outer extremity. The nuts G G may be secured in place by a suitable key or other locking device.

The rods A A extend only partially through the sleeve, and the portions of the triple 25 socket e in which they are held terminate in an upright shoulder, f, against which the ends of the two rods abut, this shoulder f being formed, preferably, near the outer end of the interior of the sleeve to give as extended 30 a bearing as possible for the rods within the socket and yet leave a sufficient depth of material behind the shoulder to withstand the longitudinal strain when the nut G is tightened on the rod B.

Upon the inner end of the sleeve E is formed 35 an outwardly-projecting flange, g, and against the flange and projecting outwardly from the surface of the sleeve is a V-shaped lug, h, adapted to be received within a corresponding 40 recess formed within the hanger H, passing around the sleeve, by means of which the beam is retained in proper position by the hanger. The inner edge of the hanger fits closely 45 against the flange g, and the beam is thus prevented from any endwise displacement which would tend to throw the brake-head 50 out of proper position with reference to the tread of the wheels, the V-shaped lug h being so located with reference to the hanger as to hold the beam so that the truss-rod extends 55 horizontally forward from the main rods in the line of the greatest strain. The outer end of the sleeve beyond the hanger forms a seat for the brake-head I, the inside of which abuts 60 against the hanger H, and is held in proper position in relation thereto by means of a lug, i, projecting from the side of the brake-head, which is engaged by a strap, j, attached to 65 the front side of the hanger. By this means the head is prevented from rocking or falling forward upon its seat and thus allowing the shoe to become unevenly worn by contact with the wheels when not in use, while the flange g prevents the disengagement of the lug i from the strap j, thus securing the brake-head in position and preventing any rocking in either direction.

The length of the sleeve E is such that when the head I is in place the outer end of the sleeve is flush with the outer edge of the head, and for the purpose of retaining the head in 70 this position a flange cap or washer, F, is provided of a larger diameter than the sleeve, and which when in position forms a flange extending outwardly beyond all sides of the end 75 of the sleeve, and thus prevents the head I from sliding away from the hanger and allowing the lug i to become disengaged from the strap j. The flange-cap F has an aperture, k, through which the end of the rod B passes, and a feather, l, formed across the inside face of the flange-cap, fits in a corresponding groove, m, formed across the end face of the sleeve and allows it to be removed when necessary.

By tightening the nuts G on each end of 80 the rod B the proper camber is given to the rods A A to adapt the face of the shoes to the coning of the tread of the wheels, the rod passing through the sleeve at one side of the center, and the rods A A abutting against the 85 shoulder f in the socket at the other side of the center, it follows that the tightening of the nut G tends to spring the ends of the rods A A in the direction of the rod B, and the face of the shoe is thus brought parallel with 90 the tread of the wheel.

For attaching a safety-hanger to prevent the falling of the beam if the hanger H should for any cause fail to furnish a proper support, two clamp-plates, n n, are used, bent at each 100 extremity to grasp the rods A A and B, respectively, and held in place by an eyebolt, o, passing through both plates, to the eye of which is attached the safety-chain p.

The outer surface of the sleeve may be of 105 any desired form to suit any of the several methods of attaching the brake head and shoe.

By the above-described construction a 110 brake-beam is produced of great strength, moderate weight, and at small expense, and the several parts can be put together without blacksmithing. If any part becomes worn, it can be replaced without other tools than a wrench, and with but a small loss of time. 115 Every part is of metal, usually wrought-iron for the rods and malleable iron for the other parts. The truss-rod can be bent sufficiently for the purpose without heating, and the main rods are sprung into place without previous bending.

I claim as my invention—

1. A brake-beam consisting of a tie-bar composed of two rods separated at their middle point, a double-inclined truss-rod, a sleeve 125 uniting the said three rods at their extremities, the said sleeve forming bearings adapted to receive a hanger and brake-head, and means, substantially as described, for adjustably cambering said tie-rods to incline 130 said sleeve-bearings to a greater or less angle from the longitudinal line of the beam.

2. A brake-beam consisting of a tie-bar composed of two rods separated at their mid-

- able point, a double-inclined truss-rod, a removable sleeve having a triple socket adapted to receive and unite the extremities of the said three rods, the said sleeve forming bearings adapted to receive a brake-hanger and brake-head, and a branching king post or strut, the said branches having bearings for said tie-rods and the opposite end of the body of the strut having a bearing for said truss-rod, substantially as and for the purpose herein specified.
3. In a brake-beam of the character described, consisting of two tie-rods and a truss-rod supported at their middle point by a forked strut, a triple sleeve removably mounted upon and retaining together the extremities of said rods, an outwardly-extending annular flange formed on the inner end of said sleeve, a V-shaped lug upon said sleeve abutting against said flange, and a brake-hanger adapted to surround said sleeve and having a recess to receive said lug, substantially as specified.
4. A brake-beam consisting of a tie-bar composed of two rods separated at their middle point, a double-inclined truss-rod, the extremities of the said tie-rods and truss-rod being brought together and united at their extremities by means of a removable sleeve forming bearings for the brake-hanger and brake-head, and the said tie-rods being cambered from their middle point, substantially as described, whereby the said sleeve-bearings are held at a slight angle to the longitudinal line of the beam.
5. A brake-beam consisting of three rods trussed together at their middle point by means of a forked strut forming the fulcrum-bar, the said rods being brought together at their extremities, a movable sleeve mounted upon and retaining said extremities together, and means for retaining said sleeve normally in position upon the extremities of the rods to form a seat for the brake-head, substantially as and for the purpose herein specified.
6. In a brake-beam of the character described, consisting of two main rods mounted in bearings formed at one end of the fulcrum-bar and a truss-rod mounted in a bearing at the opposite end of said fulcrum-bar and bent at its extremities to lie substantially parallel with the main rods, a triple sleeve having a socket of a form to receive the extremities of the three rods, the said truss-rod extending entirely through said sleeve and provided with a screw-thread and nut, whereby the sleeve may be retained in place, substantially as and for the purpose herein specified.
7. In a brake-beam of the character described, consisting of the two main rods and a truss-rod supported at their middle point by a forked strut, a triple sleeve mounted upon and retaining together the extremities of said rods, and an outwardly-extending annular flange formed on the inner end of said sleeve, substantially as and for the purpose herein specified.
8. In a brake-beam, in combination with the main rods and truss-rod, a sleeve having a triple socket of a form to fit the combined bulk of the several rods, the truss-rod extending entirely through the sleeve and provided at its outer projecting end with a screw-thread and nut, and the main rods abutting against an upright shoulder formed near the outer end of the sleeve by the termination of the portion of the triple socket in which said rods are held, substantially as and for the purpose herein specified.
9. In a brake-beam, in combination with the main rods and truss-rod, a triple sleeve mounted upon the outer united extremities of said rods and adapted to form a seat for the brake-head, the truss-rod extending entirely through said sleeve and provided at its outer projecting extremity with a screw-thread and nut, and a flange-cap of larger diameter than the said sleeve and adapted to be held in place upon the outer extremity of the truss-rod between said nut and the outer end of the sleeve, substantially as and for the purpose herein specified.
10. In a brake-beam, in combination with the main rods and truss-rod, a triple sleeve mounted upon the outer extremities of said rods and adapted to form a seat for the brake-head, the truss-rod extending entirely through said sleeve and provided at its outer extremity with a screw-thread and nut, a flange-cap of larger diameter than the said sleeve and adapted to be held in place upon the end of the truss-rod between said nut and the outer end face of the sleeve, the said sleeve having a groove formed across its outer end face, and a correspondingly-shaped feather formed across the inner face of the flange-cap, substantially as and for the purpose herein specified.
11. In a brake-beam of the character described, consisting of the main rods and the truss-rod united at their extremities and supported at their middle by means of bearings in a forked strut, the clamp-plates *nn*, adapted to grasp the several rods at the opposite extremities of the plates, and an eyebolt, *o*, passing through said plates and adapted to be connected with the supporting frame-work by means of a chain or other suitable support, substantially as and for the purpose herein specified.

In testimony whereof I affix my signature in presence of two witnesses.

HARVEY L. PRESTON.
